UNITED STATES PATENT OFFICE.

GEORGE F. STANLEY, OF DAYTON, OHIO, ASSIGNOR TO THE STANLEY MFG. COMPANY,
OF DAYTON, OHIO, A CORPORATION OF OHIO.

METAL LABEL.

Original application filed January 14, 1925, Serial No. 750,924. Divided and this application filed
March 19, 1925. Serial No. 16,684.

My invention relates to labels.

This application is a division of my co-pending application Ser. No. 750,924, filed Jan. 14, 1925.

- 5 It is the object of my invention to provide labels with paper and glue backing adapted for attachment to various articles of manufacture such as strands of pearls, beads, and the like, or similar articles.
10 It is a further object of my invention to provide such an arrangement in connection with the paper backing and adhesive surfaces so that the respective parts of the label will adhere to each other to form a permanent seal of the label upon the article without sticking to the article.

15 A still further object is to provide a label such that the wing portions may be disjoined from the article to which the label is attached without destroying the body of the label or injuring the article.

Referring to the drawings:

- Figure 1 is a plan view of one form of the label or back; and
20 Figure 2 is a perspective showing the arrangement of the layers of metal, glue, and paper in Figure 1.

25 Referring to the drawings in detail; 1 designates one half of the label, while 2 designates the other half, such halves being connected by a narrow rectangular connecting band 3.

The metal plate 7 forming the body of the

label is susceptible of being embossed and carrying various colors and color combinations.

35 The back of the body portion of the label is coated with a coating of glue 4, a coating of paper 5, and another coating of glue 6.

It will be obvious that upon a strand of 40 pearls or other articles being located between the plates 1 and 2 adjacent the band 3, that the glued surfaces of the plates may be moistened and joined together, thus forming a loop which affixes the backing to the 45 strand without applying adhesive to the strand and making it impossible to detach from the strand unless it is especially desired so to do.

50 I desire to comprehend within my invention such modifications as may be necessary to adapt it to varying conditions and uses.

Having thus fully described my invention, what I claim as new and desire to secure by Letters Patent, is:—

55 A label comprising a pair of metal plates, a bridge connecting the two plates together and adapted to be bent around an article of merchandise whereby to dispose the plates in superposed relation, and a tearable backing on the faces of the plates, said backing having an adhesive coating whereby to secure the plates together.

60 In testimony whereof, I affix my signature.

GEORGE F. STANLEY.
